Chas. H. Fowler.

UNITED STATES PATENT OFFICE.

WILLIAM SEWARD BARKER, OF TROY, OHIO.

FENCE-MACHINE.

SPECIFICATION forming part of Letters Patent No. 410,482, dated September 3, 1889.

Application filed July 15, 1889. Serial No. 317,587. (No model.)

To all whom it may concern:

Be it known that I, WILLIAM SEWARD BARKER, a citizen of the United States, residing at Troy, in the county of Miami and State of Ohio, have invented certain new and useful Improvements in Fence-Machines; and I do hereby declare that the following is a full, clear, and exact description of the same, reference being had to the annexed drawings, making a part of this specification, and to the letters and figures of reference marked thereon.

This invention relates to certain new and useful improvements in fence-making machines; and it has for its object, among others, to provide a simple and cheap fence-making machine with few parts and those easily operated and not liable to get out of order.

The invention resides in the peculiar combinations and the construction, arrangement, and adaptation of parts, all as more fully hereinafter described, shown in the drawings, and then particularly pointed out in the appended claims.

The invention is clearly illustrated in the accompanying drawings, which, with the letters of reference marked thereon, form a part of this specification, and in which—

Figure 1 is a perspective view showing a section of a fence being built by my improved machine. Fig. 2 is a side elevation of the form of twister. Fig. 3 is a perspective view of the tension device detached. Fig. 4 is a vertical section through the tension device.

Like letters of reference indicate like parts throughout the several views of the drawings.

Referring now to the details of the drawings by letter, A designates a suitable post firmly fixed in the ground or a suitable support, and is held against the tension of the fence-wires by means of the brace-wires a. This is the starting end of the fence.

B is supposed to represent the post at the other end of the fence. It is suitably secured in the ground or other support, and is braced by means of the brace-wire b, secured at its ends to the posts or pegs b', driven into the ground, the bight of the wire being held in a suitable notch b² in the post, as shown in Fig. 1.

C is a loose or sliding post, provided with suitable staples or eyes c, through which the fence-wires D are passed. This sliding post

is designed to lie flat against the post A, as shown, with the fence-wires fast thereto and embracing the said post A. Suitable means are provided to prevent vertical displacement of this sliding post. In the drawings I have shown a key c' fast to one of the posts A or C and fitting in a notch in the other. This prevents displacement of the sliding post when strain is put on the fence-wires. The strain on the fence-wires being in direct opposition to the braces a, the two posts are kept in their vertical position. The keys c' are wedge-shaped, and serve as efficient and easy means of tightening the wires when they become slack, or, by simply withdrawing the wedges a little as the wires contract in cold weather, prevent breaking of the wires.

The ends of the fence-wires are extended a short distance beyond the end post B, and are passed upon each side of a post or bar E, which is provided with suitable eyes or staples e, to receive the brace-wires f, the ends of which wires are designed to be fastened to suitable posts or other securing means in the ground or otherwise to hold the post or bar in its upright position.

The ends of the wires are passed through between my tension-blocks F, the adjacent faces of which are corrugated, as shown, and may be either of wood or metal. They are held together by means of the clamping-bolts and nuts g and h, the tightening of which increases the tension on the wires. When the section of fence has been constructed, the tension devices may be opened by loosening the nuts, the ends of the wires withdrawn, and the tension devices are ready for use in the construction of another section of fence.

I is a vertical bar provided with the lateral arms J, the number of arms corresponding to the number of fence-wires employed. There are three shown in the drawings, and the central one is extended to form a handle K, by which the twister may be operated. To the outer ends of these arms are pivoted the arms L, the central one being pivoted between the bifurcations of the central arm J, as shown in Fig. 1, and held by means of a set-screw, so that it may be prevented from turning on its pivot when desired. The arms L at their outer ends are provided with the segmental heads M, formed with a series of fingers or

holding-jaws N, which may be of the form shown in Fig. 1, or, as shown in Fig. 2, with sort of undercut portions to better hold the wires.

- 5 In practice the wires are engaged in the jaws of the heads, and the twister-frame moved up and down, which causes the heads to alternately assume the positions shown in dotted and full lines in Fig. 2, and at each 10 move of the twister-frame the wires are twisted to receive and hold the pickets. The plurality of holding-jaws on each head provides for the employment of pickets of varying sizes.

The segmental form of the heads is of material advantage, and is considered of importance in the effectiveness of the twisters from the fact that the bearing of the wires is not directly upon the holding-jaws, but upon the surface of the head, thereby removing the 15 danger of wearing channels through the jaws and rendering them liable to break off, as is the case with the straight heads with holding-jaws. The convex outer face of the head also allows of movement of the wires in the oper-

ation of twisting, the wires being guided by 25 the curved surface of the head, and the wear is thus distributed over the surface of the head, instead of being all in one place, thus increasing the life of the device.

What I claim as new is—

1. The twister-frame combined with the pivoted arms and the segmental heads at the outer ends of said arms provided with holding-jaws, substantially as described.

2. The combination, with the twister-frame 35 and the pivoted arms thereon, of the segmental heads on the outer ends of said arms, and provided with a plurality of holding-jaws extending in opposite directions from the center of the heads, substantially as and for the 40 purpose specified.

In testimony that I claim the above I have hereunto subscribed my name in the presence of two witnesses.

WILLIAM SEWARD BARKER.
